United States Patent Office

Des. 178,517

Patented Aug. 14, 1956

178,517

ELECTRIC MOTOR

Anthony G. Horvath and William H. Kuner, Dayton, and Robert L. Wolfe, Springfield, Ohio, assignors to The Master Electric Company, Dayton, Ohio, a corporation of Ohio

Application September 26, 1951, Serial No. 16,752

Term of patent 14 years

(Cl. D26—5)

Fig.-1

Fig.-2

Fig.-3

Fig. 1 is a perspective view of an electric motor embodying our new design;

Fig. 2 is an end view thereof looking from the left of Figs. 1 and 3; and

Fig. 3 is a top plan view thereof.

We claim:

The ornamental design for an electric motor, substantially as shown.
